(57) **CLAIM**

The ornamental design for a control device, as shown and described.

DESCRIPTION

FIG. 1 is a first perspective view of a control device showing a first embodiment of the new design.

FIG. 2 is a second perspective view thereof.

FIG. 3 is a top plan view thereof.

FIG. 4 is a right side elevational view thereof. The left side elevational view is a mirror image of the right side elevational view.

FIG. 5 is a bottom plan view thereof.

FIG. 6 is a front elevational thereof wherein the cap is in open position.

FIG. 7 is a rear elevational thereof wherein the cap is in open position.

FIG. 8 is a first perspective view of a second embodiment of the new design.

FIG. 9 is a second perspective view of the second embodiment.

FIG. 10 is a top plan view of the second embodiment.

FIG. 11 is a right side elevational of the second embodiment. The left side elevational view of the second embodiment is a mirror image of the right side elevational view of the second embodiment.

FIG. 12 is a bottom plan view of the second embodiment.

FIG. 13 is a front elevational of the second embodiment wherein the cap is in open position; and,

FIG. 14 is a rear elevational of the second embodiment wherein the cap is in open position.
